No. 630,665.

Patented Aug. 8, 1899.

F. P. COUSE.
LOADING FOR WHIP BUTTS.

(Application filed June 6, 1899.)

(No Model.)

UNITED STATES PATENT OFFICE.

FREDRIC P. COUSE, OF WESTFIELD, MASSACHUSETTS.

LOADING FOR WHIP-BUTTS.

SPECIFICATION forming part of Letters Patent No. 630,665, dated August 8, 1899.

Application filed June 6, 1899. Serial No. 719,536. (No model.)

To all whom it may concern:

Be it known that I, FREDRIC P. COUSE, a citizen of the United States of America, and a resident of Westfield, in the county of Hampden and State of Massachusetts, have invented certain new and useful Improvements in Loadings for Whip-Butts, of which the following is a full, clear, and exact description.

This invention relates to improvements in
butt-loadings for whips.

The principal object of this invention is to provide a loading for the butt of the whip which is applicable externally of the whip body or stock instead of internally, as heretofore usually inserted, whereby the solidity of the stock is not impaired, and which butt-loading, furthermore, conduces to impart enlargement and desirable shape to the end of the whip which is grasped by the hand.

The invention consists in the load-pieces for application exteriorly of the stock at the butt-end of the whip and to the combination therewith of the usual parts and appliances of the whip, all substantially as hereinafter fully described, and set forth in the claims.

Reference is to be had to the accompanying drawings, in which—

Figure 1 is a side view of the butt-end portion of the whip. Fig. 2 is a central longitudinal section through the whip, showing the novel combination of parts. Fig. 3 is a cross-section, on an enlarged scale, taken on the line *x x*, Fig. 1. Figs. 4 and 5 are respectively a perspective and a longitudinal sectional view through one of the load pieces or shells.

Similar characters of reference indicate corresponding parts in all of the views.

In the drawings, A represents the butt-end portion of the whip, comprised in which is the stock *a*, of rattan or wood.

B B represent the loading-pieces, of which there are preferably two, of semicircular form in cross-section and tapered from near the butt-end forwardly, more or less, in the proportion indicated in Fig. 2. Each loading-shell is also formed with the taper *b*, extending from a short distance above its lower end to such end, the same in practice being quite gradual, although shown somewhat exaggerated in the drawings. These cross-sectionally semi-annular loading-shells, which are of lead, iron, or other suitable metal, are

placed about the rattan or other material of which the butt-end portion of the whip is composed being suitably confined thereon by glue, or the confinement may be, in addition to or substitution of the glue, secured by rivets or other mechanical fastening. These loading-shells B B being applied about the stock at the butt-end, the whip is covered with the plaiting or braiding *d* in the usual manner, the same covering the loading-shells and serving as additional means for the retention of the said shells in their confinement about the stocking.

The metallic ferrule *f* or ferrule of other material is applied to cover the shoulder or line of demarcation at the forward end of the load-shells.

g represents the butt-cap or butt-end ferrule or thimble, the same having a crowding fit on the rear endwise-tapered portion *b* of the load-pieces which are covered by the plaiting.

The provision and application of the lead loading-shells B B externally of the sidings or stock at the butt portion of the whip obviates the necessity of boring or recessing such butt portion for the reception internally of a load-piece, as heretofore usually done, and thus the whip instead of being weakened at the handle end is not only strengthened thereat, but is rendered of improved and more desirable shape.

Having thus described my invention, what I claim, and desire to secure by Letters Patent, is—

1. The butt-loaded whip having externally applied about the lower end portion of its stock the metallic loading-shell consisting of segmental metallic sections, and the textile covering braided over said sectional shell, substantially as described.

2. The combination with the butt-end portion of the whip-stock of the loading-shells B each partially annular in cross-section, the overlying plaiting, the butt cap or ferrule *g*, and the forward ferrule *f*, applied as shown.

Signed by me, at Springfield, Massachusetts, this 5th day of June, 1899.

FREDRIC P. COUSE.
